UNITED STATES PATENT OFFICE.

HERRMANN ERBS AND JOHN BARTH, OF PHILADELPHIA, PENNSYLVANIA.

DESIGN FOR A SHAWL.

Specification forming part of Design No. 5,412, dated December 12, 1871.

To all whom it may concern:

Be it known that we, HERRMANN ERBS and JOHN BARTH, of Philadelphia, Pennsylvania, have invented or produced a new Design for a Shawl, of which the following is a specification:

The nature of our design is fully represented in the accompanying drawing, to which reference is made, and in which—

Figure 1 is a diagram illustrating the design as it appears when the shawl is unfolded, and Fig. 2 the shawl as it appears when folded to the wearer's figure.

The body of the shawl inclosed by the border *a* may be plain, as shown, or of a plaid pattern, as indicated in Fig. 2; or any other pattern may be adopted either for the body, border, or fringe of the shawl, the effect produced by my design being independent of the pattern of the shawl itself. At one corner of the shawl is an orna-

mental figure, *b*, which may be modified without departing from the main feature of the design; the figure, however, should be adapted to the corner of the shawl, and should be of such a character as to produce the effect exhibited in Fig. 2 when the shawl is folded to the person, the ornamental figure adding to the appearance of the shawl and imparting to it a pleasing finish.

We claim as our invention—

The design for a shawl, substantially as illustrated and described.

In testimony whereof we have signed our names to this specification in the presence of two subscribing witnesses.

HERRMANN ERBS.
JOHN BARTH.

Witnesses:

WM. A. STEEL,
HARRY SMITH.
